Atty.

UNITED STATES PATENT OFFICE.

DAVID I. LEVINE, OF WAKEFIELD, MASSACHUSETTS, ASSIGNOR TO HEYWOOD-WAKEFIELD COMPANY, OF WAKEFIELD, MASSACHUSETTS, A CORPORATION OF MASSACHUSETTS.

CAR-SEAT BACK.

Application filed September 1, 1925. Serial No. 53,901.

My invention relates to cushions having been primarily designed for application to car seat backs.

In a common form of construction of seat backs, springs are placed between pairs of broad strips of thin sheet metal which are arranged side by side on a frame to support a fabric cover, these metal strips being made long enough to allow a certain amount of bulge in both surfaces of the seat back. Heretofore the ends of these strips have been secured to the top and bottom members of the supporting frame. As a result, pressure on one portion of the seat back sufficient to push it inwardly would cause other portions to bulge further out. This detracts from the comfort of the person leaning against the seat back.

To overcome this objection I secure one end of each strip in such a way as to take up any slack caused by bending part of the strip inwardly and so prevent undesirable bulging of other portions of the strip.

A preferred embodiment of the invention is illustrated in the drawing in which:

Figure 1 is a conventional car seat in perspective. Figure 2 is an elevation of an assembled frame for a car seat back embodying the present invention.

Figure 3 is an end view of the same.

Figure 4 is a sectional view on the line 4-4 of Figure 2.

Referring to the drawing in detail, 1 represents the open framework of a conventional car seat back preferably consisting of metal channel pieces 2 and 3, the former being bent over into a U-shape to form three sides thereof, the latter constituting the fourth side. The cross section of both pieces is generally in the form of a W. Strips of wood 4, 4^a, are fitted into the middle groove of these members to provide means for tacking on fabric covers. The frame is braced by a cross bar 5.

Extending from top to bottom on either side of the frame are broad strips of thin metal 6, which are corrugated, as at 7, to prevent transverse buckling. These strips are arranged in pairs, each strip on one side of the frame being opposed by a strip on the other side. A series of springs 8 are positioned between the opposed strips of each pair and engage their inner faces, normally bulging them out, the strips thus acting as cover members for the springs. As shown, the up-

per ends of the strips are secured to frame member 2, the lower ends being preferably connected to the frame in the following manner:

A suitable number of links 10 are secured to the frame member 3. Elongated loops 11 are secured to the lower ends of the strips as by rivets 12 or may be made integral with the strips, and a rod 9 is threaded through the links and loops. If desired, the positions of the links and loops may be reversed in assembling the parts. When any of the strips are pressed inwardly so as to reduce the bulge, the elongated loops 12 permit motion of the adjacent ends of the strips substantially in the plane of the frame and toward the edge thereof. Such motion will, of course, increase the spacing between the two ends of the strip and thus obviate undesirable bulging of portions of the strip not pressed inwardly.

Instead of securing the upper ends of the strips directly to the frame and the lower ends loosely, as described, the reverse arrangement may be made, the lower ends being attached directly to the frame and the upper ends through loops or other suitable means for giving them freedom of motion toward the edge of the frame, or, if preferred, the strips may be connected to the frame loosely at both ends so that slack in the strips produced by reducing the normal bulge may be taken up by movement of either or both ends of the strip toward the periphery of the frame.

It is obvious also that this method of loosely connecting one end of each strip may be useful in cases where the strip is normally straight but subject to being bulged in use.

It is to be understood that this invention is not limited by the disclosure in the drawing and description, but is subject to such changes and modifications as fall within the scope of the appended claims.

I claim:

1. A cushion comprising an open frame member, flexible strips each fixed at one end to one side of the frame member, and means loosely connecting the other end of each strip to another side of the frame member, said connecting means comprising an elongated loop formed integrally with each strip and a rod threaded through the loops and secured to the frame member.

2. A cushion comprising an open frame member, flexible strips each fixed at one end to one side of the frame member, and means loosely connecting the other end of each strip to another side of the frame member, said connecting means comprising an elongated loop at the end of each strip, a floating rod thread-

ed through said loops and a series of spaced anchoring elements engaging the rod at points adjacent to said loops, said anchoring elements being secured to said frame. ¹⁰

In testimony whereof I have affixed my signature.

DAVID I. LEVINE.
